(57) CLAIM

I claim the ornamental design for a bulletin board kit, as shown and described.

DESCRIPTION

FIG. 1 is a front, top, right, perspective view of a bulletin board kit, showing my new design;

FIG. 2 is a front elevation view thereof;

FIG. 3 is a rear elevation view thereof;

FIG. 4 is a left elevation view thereof;

FIG. 5 is a right elevation view thereof;

FIG. 6 is a top plan view thereof; and,

FIG. 7 is a bottom plan view thereof.

Broken lines, such as those depicting the magnetic smiley face, form no part of the claimed design.

1 Claim, 7 Drawing Sheets(56)
